UNITED STATES PATENT OFFICE.

HOLDEN RINGWALT HOUGHTON, OF BALTIMORE, MARYLAND.

MATCH-BOX HOLDER.

1,167,072.

Specification of Letters Patent.

Patented Jan. 4, 1916.

Application filed June 10, 1914. Serial No. 844,148.

To all whom it may concern:

Be it known that I, HOLDEN RINGWALT HOUGHTON, a citizen of the United States, residing at Baltimore, in the State of Maryland, have invented certain new and useful Improvements in Match-Box Holders, of which the following is a specification.

This invention relates to improvements in match box holders and has particular reference to a device for detachably holding a 10 match box in a partially open condition to expose the matches for ready withdrawal from the box.

One object of the invention is to provide 15 an improved construction of holder that will permit of the ready attachment or detachment of the box whereby an empty box may be removed and a box filled with matches attached with facility, and to also provide 20 an exceedingly simple and cheap construction of holder that may be manufactured at a minimum cost whereby the device may be given away, if desired, for advertising purposes.

25 The accompanying drawing illustrates the invention wherein,—

Figure 1, shows a front face view of the device with a box of matches attached thereto. Fig. 2, illustrates the holder in perspective with the casing of the box attached thereto,—a portion of which latter is broken away to show the means for supporting the box proper in the casing. Fig. 3, shows the holder and the casing in vertical section and 30 the box proper in position within the casing, and Fig. 4, illustrates the blank from which 35 the holder is formed.

Referring to the drawing, the numeral 5, 40 designates a base plate, preferably of card-board, because of its cost, but which may readily be stamped from sheet metal. The outline of the base is also a matter of preference and may be other than that shown, but for simplicity it is shown substantially 45 rectangular. At the lower edge, the base plate 5, has a movable tongue 6, and a fold or crease 7, is provided in the material of which the base and tongue is formed, at the joinder of the base with the tongue. 50 The tongue 6, has a crosswise fold 8, therein between its free end and the base plate, and from said fold to the free end, there is provided a flange or ledge 9, for a purpose which will presently be explained. Between 55 the fold 7, at the bottom of the plate, and the opposite or top edge, said plate is pro-

vided with a slit 10, which extends downwardly from a point to one side of an imaginary central line drawn vertically across the plate and which then extends 60 upwardly after crossing said line and terminates at the other side of said central line. This slit severs the base so as to produce a movable clip or flap 11, with a down-pointing free edge 12, which latter may be readily sprung outwardly from the plate. It will therefore be noted that the clip or flap 11, has position on the plate directly over the tongue 6.

The match box which the device is designed to hold comprises a casing having front and rear walls 13 and 14 respectively, and also having parallel side walls 15 and 16, which connect the front and rear walls. At the upper and lower ends the casing is 70 entirely open. In practice it is customary for the outer faces of the side walls 15 and 16 of the casing to be provided with a material 17, to ignite the matches by frictional contact therewith. The matches 18, are retained in a receptacle in the usual way which receptacle has a rear wall 19, parallel side walls 20, and end walls 21 and 22, so that one side of the receptacle will be left open. This match receptacle slides like a drawer 80 into the casing,—the front wall 13, of which latter serves as a cover to retain the matches in the receptacle.

To attach the match box to the holder the casing is presented with its rear wall 14, 90 against the flat front surface of the base plate. The clip or flap 11, is then sprung outwardly and the casing is pushed upwardly so that the central part of the upper edge 23, of the rear wall 14, will pass under the clip 95 or flap while the side portions of said rear wall will seat against the base plate at opposite sides of the flap. During this operation the tongue 6, will have a depending position from the lower edge of the base 100 so that the lower open end edge 24, of the rear wall 14 of the casing may have position directly over or above the fold 7, that joins the tongue and base. The movable tongue 6, is next bowed and turned upwardly into 105 the open lower end of the casing so that the lower edge 24, of the casing will rest in the fold 7. When this has been done the tongue 6, will have an upwardly inclined position in the casing and the crosswise fold 8, will 110 bear against the outer or front wall 13, of the casing while the flange or ledge 9, will

extend from said front wall rearwardly and toward the inner side of the rear wall 14, of the casing, as clearly shown in Fig. 4, of the drawing. The match receptacle is 5 next inserted in the top open end of the casing and pushed down in front of the clip or flap 11, thereby clamping the clip between the rear wall 19, of the receptacle and the rear wall 14, of the casing so as to hold 10 the clip in lapped engagement with the upper edge of the casing rear wall. When the match receptacle is pushed down inside of the casing the end wall 22, of the receptacle will seat on the flange or ledge 9, of 15 the tongue which forms a stop and a support for the receptacle. When in this position the upper end of match receptacle with the matches therein will be exposed so that the matches may be conveniently withdrawn. 20 By providing a flexible tongue on the holder, the same may readily be bowed and tucked up inside of or withdrawn from the casing to attach or detach the casing.

It will be noted that the casing is secured to the base at both the upper and lower edges of its rear wall and that the tongue that engages the lower edge must be movable to enable the upper edge to be inserted under the clip 11.

25 Having described my invention what I claim is,—

1. A holder for a two part match box

which latter has an outer inclosing casing and a slidable match receptacle that slides longitudinally in the casing,—said holder 35 comprising a base plate against which the rear wall of the casing of the box may seat and provided with a downwardly-projecting engage the upper edge of the rear wall of 40 clip between its upper and lower edges to 45 the match-box casing, said base plate also having a movable tongue formed at its lower edge and extending in an upwardly and outwardly inclined direction from said lower edge said movable tongue being foldable up into the box casing and having its upper end inturned to form a ledge inside of the box casing on which the end of the match receptacle may seat.

2. A match box holder comprising a plate 50 having a yielding clip projecting therefrom and at its lower edge said plate being provided with a flexible tongue that projects upwardly and outwardly and is provided at its upper end with a flange that extends inwardly toward the plate to form a ledge in a plane between the yielding clip and the lower edge of the plate.

In testimony whereof I affix my signature in presence of two witnesses.

HOLDEN RINGWALT HOUGHTON.
